UNITED STATES PATENT OFFICE.

GEORGE ASHTON, OF CINCINNATI, OHIO, ASSIGNOR TO THE CENTRAL FROG AND SWITCH COMPANY, OF CINCINNATI, OHIO, A CORPORATION OF OHIO.

SWITCH STAND.

Application filed August 4, 1922. Serial No. 579,719.

To all whom it may concern:

Be it known that I, GEORGE ASHTON, a citizen of the United States, residing at Cincinnati, in the county of Hamilton and State of Ohio, have invented certain new and useful Improvements in Switch Stands, of which the following is a specification.

My invention relates to means for throwing the switch points into open or closed position.

The object of my invention is to provide simple, convenient, efficient, economical and easily operated means for operating the switch stand in a confined space to throw the switch points into either open or closed position.

My invention consists in providing a base having the switch throwing lever pivotally mounted thereon to be moved parallel with the track and also having a bell crank pivotally mounted on said base with one arm suitably connected to the switch throwing lever near the pivoted end thereof and having the other arm of said bell crank pivotally connected to a connecting rod suitably attached to the switch points.

My invention also consists in the construction, combination and arrangement of parts as herein set forth and claimed.

In the drawings:

Fig. 1 is a plan view of my invention;

Fig. 2 is a perspective view of the switch stand and solid connecting rod;

Fig. 3 is a side elevation of Fig. 1;

Fig. 4 is a perspective view of the switch stand showing a modified form of connecting rod to permit the switch to be run through in one direction and automatically return the switch points to closed position.

In the embodiment of my invention as illustrated and which shows a preferred construction, I provide an offset base 1 having end 2 thereof parallel with end 3. Each end is provided with suitable spike openings 4 by which the base may be securely fastened to the cross ties. End 2 is provided with a transverse bearing 5 on the upper side thereof and has journal 6 of switch throwing lever 7 pivotally mounted therein and held in place by a spring cotter 8. End 3 of said base is provided with a bearing boss 9 having a cylindrical stud 10 extending upwardly therefrom on which a bell crank 11 is mounted.

A pitman 12 is pivotally connected at

one end to arm 13 of said bell crank and is pivotally connected at its other end to said switch throwing lever at a point near its pivotal connection. Connecting rod 14 is connected at one end to the switch points 60 and at the other end to arm 15 of said bell crank. In Fig. 4 I have shown a modified construction of connecting rod 14 which is adapted to permit a train to run through the switch in one direction and to automatically return said switch points into closed position against the main rail.

The operation of the switch is very simple, easy and efficient. To close the switch merely throw the lever 7 from the position illustrated in Figs. 1, 2, 3 and 4 until it assumes the position indicated by dotted lines in Fig. 1. This movement of the switch throwing lever will operate the connecting rod through the bell crank and pitman to move the switch points.

It will be seen that this construction and arrangement may be mounted in a very narrow space upon the cross ties at one side of the track and permit the switch throwing 80 lever to be thrown parallel with the track instead of transversely thereof, thus permitting the operation of the switch stand in a very contracted or narrow space such as in a tunnel.

While I have shown and described a particular construction and arrangement of parts, it will be understood that various modifications thereof may be made without departing from the scope or spirit of 90 the invention as defined in the claims.

What I claim as new and desire to secure by Letters Patent is:

1. A switch stand comprising a base having a horizontal bearing at one end and a vertical stud at the other end thereof, a switch throwing lever mounted in said horizontal bearing, and having a weight thereon, adapted when in downwardly closed position to be entirely removed vertically from said base, a bell crank mounted on said stud and above said base and having the outer end of one arm entirely removed vertically from said base and having its other arm extending in parallel relation 100 and above said base, a pitman having one end pivotally connected to said switch throwing lever adjacent said horizontal bearing and having its other end pivotally connected to one arm of said bell crank, and 110

a switch throwing connecting rod pivotally connected to the other arm of said bell crank.

2. A switch stand comprising an S-shaped base having a horizontal bearing at one end and a vertical stud at the other end thereof, a switch throwing lever mounted in said horizontal bearing and having a weight thereon adapted when in downward position to be entirely removed from said base, a bell crank mounted on said stud and having one arm entirely removed verti-

cally from said base and having its other arm extending in parallel relation and above said base, a pitman having one end pivotally connected to said switch throwing lever adjacent said horizontal bearing and having its other end pivotally connected to one arm of said bell crank, a switch throwing connecting rod pivotally connected to the other arm of said bell crank, and a yieldable means connected to said connecting rod adjacent said switch stand.

GEORGE ASHTON.
